UNITED STATES PATENT OFFICE.

HENRY A. F. PETERSEN, OF NEW YORK, N. Y.

VALVE.

No. 820,598.

Specification of Letters Patent.

Patented May 15, 1906.

Application filed June 20, 1905. Serial No. 266,088.

To all whom it may concern:

Be it known that I, HENRY A. F. PETERSEN, a citizen of the United States, residing at the city of New York, borough of the Bronx, in the county and State of New York, have invented certain new and useful Improvements in Valves, of which the following is a full, clear, and exact specification.

My invention relates to improvements in means for controlling the passage and operation of fluids under pressure; and the same has for its object more particularly to provide a simple, efficient, and reliable valve adapted for use in connection with steam-boiler, refrigeration, or other plants in which fluids under pressure are employed or circulated.

Further, said invention has for its object to provide a valve which will automatically operate to shut off or control the passage of the fluid therethrough when a break occurs in some part of the system or apparatus or any other condition intervenes which will result in a variation of the pressure on one side of the valve or the other—as, for example, where a battery of steam-boilers is employed and a tube breaks in one of the units, the valve interposed between said unit and the main steam pipe or line will at once automatically close and disconnect the said unit from the remainder of the battery without causing any material loss in pressure of the remainder of said battery.

To the attainment of these ends my invention consists in the novel details of construction and in the combination, connection, and arrangement of parts hereinafter more fully described and then pointed out in the claims.

In the accompanying drawings, forming part of this specification, wherein like figures of reference indicate like parts, Figure 1 is a central longitudinal section taken on the line 1 1 of Fig. 2, illustrating a valve made according to and embodying my said invention; and Fig. 2 is a transverse section of the same, taken on the line 2 2 of Fig. 1.

In said drawings, 10 designates a cylindrical valve-casing having a flanged inlet portion 11 at the center of its under side and a flanged outlet portion 12 at its upper side opposite to said inlet portion.

13 denotes a partition extending transversely across the interior of the casing 10 and dividing the same into two separate compartments 14 15. The partition is pro-

vided with a circular screw-threaded opening into which is fitted a screw-threaded annular bearing or valve-seat 16. Upon the opposite ends of the casing 10 are bolted heads 17 17', having hollow cylindrical portions 18 18', respectively, the interior portions of which are in alinement and communicate with the interior of the casing 10.

19 denotes a valve-stem which extends through the cylindrical portion 18' of the head 17' and into the casing 10 and cylindrical portion 18 of the head 17, and 20 denotes a stuffing-box provided in the end of the head 17', through which the end of the valve-stem 19 passes.

Upon the portions of the valve-stem 19 within the cylindrical portions 18 18' the heads 17 17' are secured hollow pistons 21 21', respectively, and upon the portions of said valve-stem within the compartments 14 15 are secured flat circular valves 22 22', which are held duly in position upon said valve-stem and separated from each other and the pistons 21 21' by tubular spacing-sections 23, arranged upon the valve-stem 19. 24 denotes a bracket which is secured at one end to the under side of the cylindrical portion 18' of the head 17' and carries at its outer end a pivoted lever 25, which is pivotally secured at its upper end to the projecting end of the valve-stem 19 by a link 26.

The cylindrical portion 18 of the head 17 is provided adjacent to its outer end with a port 27 and the flanged inlet portion 11 of the casing 10 with a similar port 28, and 29 denotes a pipe connected to said cylindrical portion 18 and inlet portion 11 and communicates with the interiors thereof through the ports 27 28 therein. The cylindrical portion 18' and outlet portion 12 are provided, respectively, with similar ports 30 31 and connected together by a pipe 32. 33 33 denote pet-cocks provided in the inlet and outlet portions 11 12 of the valve.

The valve is to be arranged in the riser extending from the boiler to the line and interposed between the stop-valve and the line where only one stop-valve is employed or between the stop-valves where two are employed.

The operation is as follows: The valves 22 22' should be adjusted by means of the lever 25 to the position shown at Fig. 1, which is the normal. As soon as any variation in the pressure occurs in any way, on one side of the

valve or the other a portion of the steam in the higher-pressure side passing through the casing 10 will also find its way into the pipe 29 or 32, as the case may be, and enter the 5 end of the cylinder 18 or 18' and force the piston therein inward and slightly move the stem 19 and valves carried thereby and cause one of said valves to seat itself upon the seat 16 in the partition 13 and be thereaf-
ter forced firmly against its seat by the pressure of the steam in the compartment of the higher-pressure side. As soon as the cause 10 of the trouble has been corrected the valve may be again instantly restored to its initial 15 position by means of the lever 25, which will also indicate the position of said valve. The excess of pressure may be relieved or the pressure varied upon one side of the valve or the other by simply opening one or the other 20 of the petcocks 33, as required.

It will of course be understood that the invention is not confined to steam-boilers, but may be utilized for many purposes in which fluids under pressure are employed or con- 25 trolled—as, for example, in an ammonia plant between compressor and condenser.

Without limiting myself to the details of construction, which may be varied within the scope of the invention, what I claim, and 30 desire to secure by Letters Patent, is—

1. A valve for the purposes specified, comprising a casing, a plurality of valves therein, and means adapted to operate under variation of pressure of the operating fluid to ac- 35 tuate certain of said valves to prevent the passage of said fluid therethrough in either direction, substantially as specified.

2. A valve for the purposes specified, comprising a casing, auxiliary means connecting 40 said casing with the line adjacent to the inlet and outlet portions of said casing, a plurality of valves therein, and means therein operating in response to variations in the pressure of the operating fluid to actuate said valves 45 to control the passage of said fluid therethrough, substantially as specified.

3. A valve for the purposes specified, comprising a casing, a plurality of connected valves therein, and means adapted to operate under influence of the operating fluid to ac- 50 tuate a part of said valves to prevent the passage of fluid therethrough as the pressure thereof is caused to vary in the line to either side of said casing, substantially as specified.

4. A valve for the purposes specified, comprising a casing, auxiliary means connecting said casing with the line adjacent to the inlet and outlet portions of said casing, valves ar- 60 ranged therein, a stem for said valves, pistons on said stem adapted to work in said casing under influence of the operating fluid, and actuate said valves to control the passage of said fluid therethrough, substantially as specified.

5. A valve for the purposes specified, com- 65 prising a casing having cylinders therein, com-

municating with the inlet and outlet portions of said casing, a stem arranged in said casing, pistons on said stem, adapted to work in said cylinders, valves arranged upon said stem intermediate said pistons, said pistons being adapted to operate under influence of the operating fluid to actuate certain of said valves to control the passage of fluid therethrough in either direction, substantially as specified. 70

6. A valve for the purposes specified, comprising a casing having cylinders at its opposite ends communicating with the inlet and outlet portions of said casing, a stem arranged in said casing, pistons secured upon said stem and adapted to work in said cylinders, valves 80 arranged upon said stem intermediate said pistons, and means arranged without said casing for actuating said pistons and valves, substantially as specified. 75

7. A valve for the purposes specified, comprising a casing having cylinders arranged at its opposite ends communicating with the inlet and outlet portions of said casing, a stem arranged in said casing having pistons arranged thereon upon the portions within the cylinders, and valves upon said stem intermediate said cylinders and pistons thereon, substantially as specified. 90

8. A valve for the purposes specified, comprising a casing having cylinders arranged at its opposite ends in alignment with each other and communicating with the inlet and outlet portions of said casing, valve-seats in said casing intermediate said cylinders, a stem arranged in said casing and cylinders, having pistons arranged thereon upon the portions within said cylinders, and valves intermediate said pistons and seats, substantially as specified. 95

9. A valve for the purposes specified, comprising a casing having cylindrical heads secured to its opposite ends communicating with the inlet and outlet portions of said casing, a partition in said casing having valve-seats therein, a stem arranged in said casing and extending through the partition therein and into the cylindrical heads and adapted for longitudinal movement therein, pistons arranged upon said stem within the cylindrical ends, and valves fixed upon said stem intermediate the pistons thereon, and the sides of the partition aforesaid, substantially as specified. 105

10. A valve for the purposes specified, comprising a casing having cylindrical heads secured to its opposite ends communicating with the inlet and outlet portions of said casing, a transverse partition in said casing having an opening therein, a bearing arranged in said opening, a stem arranged partly within and partly without said casing and cylindrical heads, pistons arranged thereon within said cylindrical heads, and a valve fixed on said stem intermediate each piston and the partition aforesaid, and means arranged with- 115 120 125 130

out said casing connected to the projecting end of the stem for actuating and adjusting the same, substantially as specified.

11. A valve for the purposes specified, comprising a casing having hollow cylindrical heads bolted to its opposite ends, pipes secured thereto and the inlet and outlet portions of the casing, a transverse partition in said casing having an opening therein, an annular bearing secured in said opening, a stem arranged partly within and partly without said casing and cylindrical heads having pistons arranged thereon within said cylindrical heads, and a valve fixed on said stem interme-

diate each piston and the partition aforesaid, 15 a bracket secured to the outer side of said casing, a lever pivotally mounted therein, and a link connecting one end of said lever with the projecting end of the stem extending through said casing, substantially as specified. 20

Signed at the city of New York, in the county and State of New York, this 16th day of June, 1905.
